(57) **CLAIM**

The ornamental design for an abutment for dental implant as shown and described.

DESCRIPTION

1. Abutment for dental implant
2. Abutment for dental implant

1.1 : Perspective

1.2 : Front

1.3 : Back

1.4 : Left

1.5 : Right

1.6 : Top

1.7 : Bottom

2.1 : Perspective

2.2 : Front

2.3 : Back

2.4 : Left

2.5 : Right

2.6 : Top

2.7 : Bottom

The claimed design is an abutment for dental implant that could be used for medical purposes in dentistry.

The broken lines depict portions of the abutment for dental implant that form no part of the claimed design.

The dash-dot broken lines are directed to the boundary lines of the abutment for dental implant, which form no part of the claimed design.
